US00D837366S

(12) **United States Design Patent** (10) Patent No.: **US D837,366 S**
(45) Date of Patent: **** Jan. 1, 2019**

(54) **AUTOMATIC SYRINGE**

(71) Applicant: **MEDIHUB. CO., LTD**, Gyeonggi-Do (KR)

(72) Inventor: **Hyeon-chul Yeom**, Gunpo-si (KR)

(**) Term: **15 Years**

(21) Appl. No.: **35/504,016**

(22) Filed: **May 19, 2017**

(80) **Hague Agreement Data**

Int. Filing Date: **May 19, 2017**

Int. Reg. No.: **DM/096721**

Int. Reg. Date: **May 19, 2017**

Int. Reg. Pub. Date: **Nov. 24, 2017**

(51) LOC (11) Cl. **24-02**

(52) U.S. Cl.

USPC **D24/113**

(58) **Field of Classification Search**

USPC D24/112-115, 130

CPC .. A61K 2300/00; A61K 45/06; A61K 9/0014;

A61L 31/16
